UNITED STATES PATENT OFFICE.

ALONZO L. EDWARDS, OF WHEELING, WEST VIRGINIA, ASSIGNOR TO WHEELING STAMPING COMPANY, OF WHEELING, WEST VIRGINIA, A CORPORATION OF WEST VIRGINIA.

LANTERN.

1,113,107.

Specification of Letters Patent.

Patented Oct. 6, 1914.

Application filed March 12, 1914. Serial No. 824,190.

To all whom it may concern:

Be it known that I, ALONZO L. EDWARDS, a citizen of the United States, and a resident of Wheeling, in the county of Ohio and State of West Virginia, have invented a new and useful Improvement in Lanterns, of which the following is a full, clear, and exact description, reference being had to the accompanying drawings, in which—

10 Figure 1 is a side elevation, partially in section, of one form of my improved device attached to one form of tubular lantern; Fig. 2 is a sectional view on the line II—II of Fig. 1; and Fig. 3 is a similar view showing the parts in a different position.

15 My invention relates to an improvement in globe retainer lifting devices, and is designed to provide a cheap and simple device of this character in which the majority of 20 the parts are concealed within the dome of the lantern or the globe retainer.

Another object of my invention is to provide a device of this character in which the spring for holding the globe retainer in position on the globe is also arranged to hold the globe retainer in its elevated position when it has been lifted from the globe.

The precise nature of my invention will be best understood by reference to the 30 accompanying drawings which will now be described, it being premised, however, that various changes may be made in the details of construction and general arrangement of the parts without departing from the spirit 35 and scope of my invention, as defined in the appended claims.

Referring to the accompanying drawings, the numeral 2 designates the usual oil well or pot, and extending upwardly from this 40 oil well are the air tubes 3, to the upper ends of which is connected a dome having an outer shell 4 and an inner shell 5. Connected to the top of the dome is the usual top plate 6. Telescopically connected with 45 the dome is a globe retainer having inner and outer shells 7 and 8, respectively; the inner shell being telescopically connected with the inner shell 5 of the dome, while the outer shell engages a flange on an annular 50 plate 9, connected to an annular flange on the lower end of the outer shell 4 of the dome. Surrounding the inner shell 5 of the dome and the inner shell 7 of the globe retainer is a coiled spring 10, which engages 55 the dome and the globe retainer for nor-

mally holding the globe retainer in its lowermost position.

11 designates the burner, and 12 a globe supporting plate which is pivotally connected to the lantern in any manner, so that 60 it is adapted to swing onto and off from the burner 11.

13 is the lantern globe supported on the plate 12 and held in position thereon by means of the spring bails 14 connected to the 65 plate 12. The lower end of the globe retainer is flared outwardly and shaped to fit the upper end of the globe and is also reinforced by a wire 15 which may be provided with opposite loops 16 for engaging guide 70 rods 17, secured to the air tubes 3.

Extending through openings in the upper end of the inner shell 5 of the dome is a rod 18; and journaled in openings in the globe retainer is a crank shaft 19 having an operating lever 20 and a crank 21. This crank 21 is offset at a point intermediate its bearings, and this offset portion is connected to the pin 18 by a link 22. The stem of the crank shaft 19 extends laterally between one 80 of the guide wires 17 and the air tube to which it is connected, while the operating handle 20 of this crank is arranged to engage the side of the tube adjacent thereto when in its extreme positions.

If desired the loops 16 may be eliminated as the crank shaft 19 will retain the parts in their proper position; and if the globe retainer is lowered when the globe has been 85 swung on its pivotal connection, the retainer can only be moved down sufficiently to bring the operating handle 20 into engagement with the tube 3. This movement is not sufficient to disengage the shells of the globe retainer from the shell or flange 90 of the dome.

By reference to the accompanying drawings, it will readily be seen that the crank 21 is placed off center with relation to the operating handle 20, so that when the globe 100 retainer is elevated, as shown in Fig. 3, the spring 10 will hold it in its elevated position, the operating handle 20 resting against the air tube 3 180 degrees from the position shown in Fig. 1, and when the device is in 105 its lowermost position, the operating handle 20 is slightly distant from the air tube 3. If the globe were not in position the globe retainer would be moved downwardly a 110 slight distance farther and just sufficient to

bring the operating handle into engagement with the tube 3, but not sufficient to move the shells 7 and 8 of the globe retainer out of engagement with the dome.

5. When it is desired to light the lantern, the operating handle 20 is moved upwardly from the position shown in Fig. 1 approximately 180 degrees so that the crank 21 will move from the position shown in Fig. 2 to 10 the position shown in Fig. 3 and slightly past the center to enable the spring 10 to hold the operating handle 20 against the tube 3. The globe and plate 12 are then 15 swung on their pivotal connection to expose the wick, and after the wick has been lighted, the globe is returned to its normal position, and the retainer lowered to the position shown in Figs. 1 and 2, at rest on the upper portion of the globe.
20. The advantages of my invention result from the provision of an extremely simple and efficient globe retaining lifting device in which the greater portion of the operating mechanism is concealed within the globe retainer and the dome, and in which the 25 spring is arranged to hold the globe retainer in both its extreme positions. A further advantage results from the provision of an operating handle which is so positioned that it will act as a stop when the globe retainer is raised to its uppermost position, and also when it is lowered to its 30 lowermost position when the globe is removed.

35. I claim:

1. A lantern having a vertically movable globe retainer at its dome portion, and a lifting device for said retainer, said lifting device being journaled in the retainer, and 40 also having a fulcrum within the retainer, which fulcrum is carried by the dome; substantially as described.

2. A lantern having a dome, a vertically movable globe retainer, a globe support, a 45 globe supported thereon, means for holding the globe retainer in contact with the globe, a crank shaft rotatably mounted in the globe retainer, and a swinging link connected to said shaft and to a fixed portion of 50 the lantern, substantially as described.

3. A lantern having a dome, a vertically movable globe retainer, a globe support, a globe supported thereon, a spring interposed between the dome and the globe 55 retainer arranged to move the globe retainer downwardly with relation to the dome, a crank shaft journaled in the globe retainer, and a crank on said shaft within the globe retainer, a link pivotally connected to said 60 crank and to the dome, said shaft having an operating handle, substantially as described.

4. A lantern having a dome, a vertically 65 movable globe retainer mounted therein, a globe support, a globe thereon, a spring interposed between the dome and the globe

retainer and arranged to move the latter downwardly with relation to the dome, a crank shaft journaled in the globe retainer, a crank on said shaft within the globe retainer, a link pivotally connected to said 70 crank and the dome, said shaft having an operating handle, and a guide for said crank shaft on the lantern, substantially as described.

5. A lantern having a dome, a globe retainer telescopically connected therewith, a crank shaft rotatably mounted in the globe retainer, a link connected to said crank and to the dome, said crank shaft and link being arranged to move the globe retainer 80 from one extreme position to the other extreme position, means for limiting the movement of said crank shaft, and a compression spring arranged to retain the globe retainer in both of its extreme positions, substantially as described.

6. A lantern having a dome, a globe retainer slidably connected thereto, a crank shaft rotatably mounted in the globe retainer, a crank on said shaft having a plurality of offsets, one of said offsets being arranged to position the crank shaft within the retainer, and a link pivotally connected to the dome and the crank and seated within the second offset, substantially as described.

7. A lantern having a dome, a globe retainer slidably connected thereto, a crank shaft rotatably mounted in the globe retainer, and formed with a crank having a 100 plurality of offsets, one of said offsets being arranged to position the crank shaft within the retainer, and a link pivotally connected to the dome and to the crank within the second offset, said crank shaft having an 105 operating handle, substantially as described.

8. A lantern having a dome, a globe retainer slidably connected thereto, a crank shaft rotatably mounted in the globe retainer, a crank on said shaft having a plurality of offsets, one of said offsets being arranged to position the crank shaft within the retainer, a link pivotally connected to the dome and to the crank within the second offset, said crank shaft having an operating handle, and a vertically disposed guide for the crank shaft, substantially as described.

9. A lantern having a vertically movable globe retainer, a crank shaft journaled in said retainer, and a swinging link connecting said shaft with the dome portion of the lantern, substantially as described.

10. A lantern having a vertically movable globe retainer, a crank shaft journaled in said retainer, and a fulcrum within the dome engaged by the crank of said shaft, substantially as described.

11. A lantern having a vertically movable globe retainer, a crank shaft journaled in said retainer, and a movable fulcrum within 130

the dome engaged by the crank of said shaft, substantially as described.

12. A lantern having a vertically movable globe retainer at its dome portion, and a lifting device for said retainer, said lifting device being journaled in the retainer, and a fulcrum member depending within the retainer from a fixed portion of the

dome and engaged by the lifter device; substantially as described.

In testimony whereof, I have hereunto set my hand.

ALONZO L. EDWARDS.
